UNITED STATES PATENT OFFICE.

FRANCIS H. RICHARDS, OF HARTFORD, CONNECTICUT, ASSIGNOR TO SAMUEL M. GARDENHIRE, OF BROOKLYN, NEW YORK.

MACHINE FOR MAKING TYPES AND TYPE-BARS.

No. 919,218.

Specification of Letters Patent.

Patented April 20, 1909.

Application filed December 20, 1900. Serial No. 40,575.

To all whom it may concern:

Be it known that I, FRANCIS H. RICHARDS, a citizen of the United States, residing at Hartford, in the county of Hartford and 5 State of Connecticut, have invented certain new and useful Improvements in Machines for Making Types and Type-Bars, of which the following is a specification.

This invention relates to a machine for 10 making types and typebars, and especially to a mechanism for making from a solid blank or bar of metal a typebar adapted for use in the typographic art for printing a line of characters.

15 The present invention is in the nature of an improvement upon that shown, described, and claimed in the application of Darien W. Dodson, Serial No. 600,151, filed July 22, 1896, to which I have permission to refer.

20 In said Dodson machine the separate types are formed on the edge of a typebar-blank by first removing excess material from the edge of such a blank to set off a solid type-blank and then subjecting the face of this type-

25 blank to the compressing action of a type-die to form a type. In said Dodson machine the removal of the excess material is effected usually by reducing or slotting the edge of the typebar-blank at two separated points to

30 set off between the slots a solid type-blank, and the die preferably operates upon the latter with a rolling movement to form the type. This rolling movement, however, in the Dodson machine is a simple one, it being 35 a progressive cycloidal movement in a proper orbit.

Prior to the construction of the Dodson machine many efforts had been made to produce a machine capable of forming by compression in solid blanks or sheets lines of 40 composed types or type-faces, but in these experiments there was, so far as I am aware, no proper recognition of the fact that it is impossible to form in this manner clear-cut

45 types suitable for the production of printed impressions without removing those portions of the face of the stock between adjacent characters. The presence of this surplus material renders it impossible to form in a 50 blank by compression a series of characters disposed sufficiently near to one another to meet the ordinary commercial requirements of typography.

In the Dodson machine it has been demon-

strated that, by providing means for setting 55 off successive portions of a suitable blank from the body of the stock, types may be formed by compression in such set-off portions without in any way disturbing the position of any other portion of the typebar-blank; that is to say, the surrounding un- 60 compressed stock will not be affected by the compression of a set-off segment thereof to form in such segment a type or character, nor will the operation of any finished type be 65 affected, either by a disturbance of the relative position of such type due to compression caused by flowage of surplus stock from an adjacent type, or by the clogging of the face 70 of such finished type through overriding of the displaced metal. In said Dodson machine the setting off of the type-blanks is usually accomplished by slotting the edge of 75 a typebar-blank at two separated points, and the type-blank set off or isolated by the cutting of these notches is usually faced at one or both of its side edges before being impressed by a type-die. When the die is brought down upon the blank a considerable portion of the metal of the type-bar blank is 80 forced out endwise of the typebar-blank and partially fills the slots or notches adjacent to the type-blank, and hence these slots serve to accommodate the flowage from the type-blanks. 85

The present mechanism, as before stated, is in the nature of an improvement upon that of Dodson, and, broadly speaking, the same result is attained by both—viz., the formation of adjacent types in a solid blank by removing excess material not required for the making of said types—but the operation of the present machine differs in many respects from the operation performed by the Dodson machine and marks a distinct advance in the 90 manufacture of typebars, especially when the quality of the product resulting from the operation of such machine is considered. 95

My present invention is also in the nature of a companion mechanism to the mechanism shown, described, and claimed in my applications Serial Nos. 79,360, filed October 21, 1901, and 79,359, filed October 21, 1901, in which applications there are disclosed two species of mechanisms for forming a type 100 upon a typebar-blank without previously setting off a type-blank; that is to say, in 105 said applications I have illustrated two

specific machines for forming a type upon the edge of a typebar-blank without first reducing or removing material in advance of the metal from which such type is to be formed. Two of the principal features which distinguish the operations of my said companion machines from that of Dodson are these: I avoid the necessity of setting off a finished type-blank before the die is brought into action, and I subject each type-formative portion of the blank to repeated type-forming operations, preferably of such a character that not only will the face of the type be perfectly finished but the base portion will also be finished and strengthened to such an extent as to enable it to resist greater crushing forces and last longer.

My present invention is a machine for making types and especially type bars which differs generically in its operation from the Dodson machine and from each of the machines shown in my said companion applications, because in my said companion applications the space in advance of any individual type is not formed independently of, but is dependent for its formation upon, the formation of such type, whereas in the present case not only is the mechanism distinguishable from that of Dodson by reason of the fact that it does not form a space in advance of each type prior to the formation of such type, but it is also distinguishable from the machines described in my said companion applications by reason of the fact that each space is formed by the mechanism by an operation entirely independent of the operation which forms the type preceding such space. In my said companion applications the formation of the space in advance of the type is dependent upon the formation of such type, for the reason that in such case the space is formed by a wall of the die which forms the type, whereas in the present case the formation of a space in advance of a type is not dependent upon the formation of such type for the reason that in this case the space and the type are formed by separate and independent members or elements, the type being formed in this case by a die which is rolled in contact with the edge of the blank, and the space being formed by a rotary milling-cutter also operative in contact with the edge of such blank.

In forming a type on a typebar-blank by means of my improved type-making mechanism I employ a device or die for compressing a portion of the blank while such portion is supported at its forward side, and in making a space in advance of such type, I employ a space-forming device for removing material from that portion of the typebar-blank which is in advance of such type, after the type-forming operation has been completed, this being one species of mechanism for making a type and a space in advance of such

type independently without first forming the space, another species of such mechanism being shown, described, and claimed in my companion application Serial No. 40,086, filed December 17, 1900, which covers a mechanism having type-forming and space-forming means operative for forming a type and a space in advance of such type independently and synchronously, the type-forming means and the space-forming means beginning and completing their operations upon the blank simultaneously.

In all of my said applications hereinbefore referred to a type-die is employed to compress or roll the edge of a typebar-blank while in contact therewith, the compressing action being exerted in such a way as to force most of the surplus stock sidewise of the typebar-blank, instead of endwise thereof as in the Dodson machine, this surplus material so forced out being removed or severed from the bar preferably after the completion of the type. During the type-forming operation the portion of the typebar-blank which is being operated on is confined endwise of the blank preferably between two separated lines, one of which in this case defines the inner rear wall of the die and the other of which is substantially the line of separation of the type and the space to be formed in advance of such type. In other words, the material being operated on to form a type is confined at its rear side by the inner rear wall of the die and is confined or supported at its forward side by the adjoining space-formative stock which has not been removed up to the commencement of the type-forming operation; and while it should be noted that the type-formative portion of the blank is confined, and an adequate support for the type preserved throughout the operation of the type-forming means, yet it will be seen also that in this case the confinement and support of the type-formative material are not due at all to the presence of a space-forming blade dependent for its operation upon the operation of the die, as is the case in my aforesaid companion applications Serial Nos. 79,360 and 79,359. As in said applications, however, practically all of the surplus stock within any type-field may be forced beyond the limits of such field in a direction transverse to the blank without disturbing the stock of any adjacent field, the flowage being almost entirely in a direction crosswise of the typebar-blank and the metal so forced out being afterward severed from the typebar-blank if it projects beyond the planes of the sides of the latter, as is usually the case. In all of my applications hereinbefore mentioned an important feature of the mechanism is type-forming means operative for gradually forming a type by repeatedly rolling a transverse portion of the edge of a typebar-blank while

the edge is in contact with the type-forming member or die, one of these members, in the present instance the die, being preferably reciprocated rapidly in a curvilinear path in 5 order that the type during formation may be subjected to such repeated rollings; and moreover a feed movement may be imparted to one of the members to bring it more and more fully into engagement with the other, 10 the result being that the type is gradually shaped to its finished form by a series of operations which serve conjointly to finish the type perfectly and also to strengthen the body of the type very materially during the 15 shaping of the latter.

When a blank is rolled while in contact with a die it is not essential that either of these members be operated in such a way as to have a rolling movement, but merely that 20 the movement imparted to such member be of a character for affecting the reduction of the blank by a rolling process. In the present case, however, a rolling movement is imparted to the die itself, and all of the various 25 operations to which the material is subjected during the making of a type result from two movements—viz., a rolling movement of one member of the mechanism and a feed movement of one member toward the other—and 30 in every case where these two movements are produced by operating one or both of the parts just mentioned each type will be formed gradually and the type-formative material will be subjected to various operations 35 that will condense the metal little by little and gradually form a wrought-metal type. The principal operations to which the material will be subjected will be the rolling of the upper or face portion of the 40 blank, the swaging of the face of the type, and the forging of the end walls thereof, and all of these operations may be performed most advantageously by a single type-forming die. The order in which said operations 45 occur may, of course, vary, as may also the duration and extent of the same, and as any one of these factors is varied the manner in which, and the extent to which, the material is acted upon and shaped will show a corre- 50 sponding variation. In every case, however, I deem it desirable to employ means for shearing out a type-block, usually on the edge of a typebar-blank, and for rolling the material at opposite sides of such blank 55 away from the latter and preferably beyond the sides of the type-bar blank, this material outside of the sheared type-block containing most of the excess which it is necessary to get rid of if types are to be formed thereon in 60 close succession. When such material between the sides of the typebar-blank is rolled in this manner substantially all of the flowage is in a direction transverse to the blank and there is practically no flowage 65 lengthwise of the bar, especially when the

rolled portion of the stock during the operation of the type-forming means is substantially continuous with the remainder of the typebar-blank.

It is essential that the major portion of the 70 surplus material be gotten rid of by removing it, as by rolling it, from a point where it will interfere with the formation of a type to a point where it will not so interfere, and preferably to a point or points beyond the sides 75 of the bar, and the type itself is formed by shaping the material of the central type-block sheared from the mass at any given point. In the present case the type-die operates upon this surplus material and upon 80 the type-block or type-blank simultaneously, and during the time that the excess material is being rolled beyond the sides of the bar the type-block is also being shaped to bring it to its finished form. When the blank and 85 the die are in contact with each other and one of them is rolled, and a feed movement is also imparted to one of them to advance it toward the other, the type-blank will be sheared gradually from the mass and the 90 surrounding material will be rolled off while the shearing operation is taking place. Moreover the type-die will also operate upon the type-blank to shape the same into a type before the completion of the shearing action, 95 and also, of course, before all of the surrounding excess material has been rolled beyond the sides of the bar. As the rolling and feed- 100 ing operations continue the base of the type-block is reduced at opposite sides of the bar, the metal condensed by a forging action, and the upper portion of the type-block forced up to fill the die, which serves to swage the face of the block and shape the face of the type. Thus not only may the die be com- 105 pletely filled and the face of the type perfectly formed, but the end walls of the latter will be so condensed by the forging operation of the die as to form a base having the maximum amount of strength for supporting the 110 head of the type and resisting any crushing forces that may be exerted upon the latter when in use.

The operation of the space-forming means is not only entirely independent of the type- 115 forming action, but it need not be at all analogous thereto. This is the case with the present invention, in which the type-forming means operates to roll the edge of the typebar-blank and the space-forming means 120 forms a space in advance of the type by gradually cutting or milling away the stock after the type has been finished, said space-forming means, of course, serving merely to remove material from the blank and exerting no 125 compressing or condensing action thereon. In operating this mechanism the space-forming means does not begin to remove material in advance of a type until such type has been completed; that is to say, not only are 130

the type-forming and space-forming operations entirely independent of each other, but the latter does not begin until the former ceases, and thus the material in advance of 5 the forming type, and which serves as a means for resisting the type-forming action and supporting the type at its forward side, is not removed, nor is it at all weakened, until the type-forming operation is at an end 10 and the type finished. When the type-forming and space-forming means shape the typebar-blank in this manner it will be evident that there is a solid body of resistant material at the forward side of the forming 15 type during the whole of the type-forming operation, and that the material in the type-field and the material in the space-field are directly connected to each other and the type-field supported by a substantially horizontally-disposed mass of stock, as well as by a 20 vertically-disposed thrust-resisting body of metal, throughout the whole period during which the type-forming means is rolling the bar to form a type. That improvement in 25 machines for making typebars in which the type-forming means and the space-forming means operate upon the blank independently, but in which the space-forming means operates upon the stock substantially synchronously with the type-forming means, is 30 not set forth herein but constitutes the subject matter of my companion application Serial No. 40,086, filed December 17, 1900.

In the drawings accompanying this specification and forming part of the present application, Figure 1 is a side elevation of a typebar-machine constructed in accordance with my present invention. Fig. 2 is an end elevation of the same looking from the right 40 in Fig. 1. Fig. 3 is a plan of the same. Fig. 4 is an enlarged, perspective view of the principal parts of the blank-holding and feeding mechanism. Figs. 5, 6, and 7 are, respectively, enlarged, sectional end elevations of the die-wheel in operative relation 45 with a typebar-blank, and illustrate three relative positions of the die-wheel and one of its dies with respect to such blank, and show not only different stages in the type-forming operation but also the beginning of 50 the rolling on of the die, the central working position thereof, and the rolling off of said die in forming a type by repeated rollings. Fig. 8 is a diagram illustrating the movements of the die-carrier during the operation 55 of forming a type. Figs. 9 and 10 are, respectively, a sectional end elevation of a typebar-blank and the space-forming tool, and a sectional side elevation of said tool and blank, in inoperative relation with each other; and Figs. 11 and 12 are views corresponding 60 to Figs. 9 and 10, respectively, and illustrating the space-forming tool at the limit of its working movement.

Similar characters designate like parts in 65 the different figures of the drawings.

As has been hereinbefore stated, the Dodson machine for forming types from cold metal produced typebars suitable for the purposes of typography; but it is desirable 70 for many reasons to make types and typebars of the very highest quality, and one of the principal objects of the present invention is to attain this result and thus form typebars that will withstand the most rigid tests 75 of commercial use. In order to accomplish this result it has been found advantageous to employ type-forming means operative for compacting and condensing most perfectly the material of the type proper before the completion of the same both at the 80 face of the type and near the base thereof, and the many experiments that have been made have demonstrated that the dies fill most perfectly and the types are of maximum strength when the type-forming means is operated to roll the material repeatedly 85 and gradually form each type by a series of operations, and the present machine embodies means for producing this result. 90

The several operative parts of the mechanism may be mounted on any suitable framework, such, for example, as a base or bed 2, supported in this case on legs in a well-known manner, and this bed-plate may have an upright or plate 3 rising therefrom and embodying a pair of long bearings 3' and 3''. The bearing 3' may serve to support a long pin or stud 30, said pin or stud preferably having mounted thereon a lever, such as T, which in 100 this case constitutes a part of the type-forming mechanism, and has a cheek 30' in engagement with the corresponding cheek of the bearing 3'. Said lever may have the usual handle at the upper end thereof, and is 105 intended to support for rotation thereon while moving in an orbital path a die-carrier, such as D, which may have formed thereon or secured thereto a plurality of dies, such as d. The orbital path in which this die-carrier 110 moves may be a relatively short one, and in the present case the hub or shaft of the die-wheel, which hub or shaft is indicated herein by 4, is movable in a slot 3''' in the wall 3, and is limited in its movements by the stop 115 walls at the ends of such slot, said shaft preferably having at the end thereof opposite the die-wheel a knurled head 4' for turning the same. It will be noticed by referring to Fig. 1 that the major portion of this slot is disposed at one side of a central, vertical line passing through the axis of the lever T, and also that said line passes through the center of the face of the typebar-blank to be operated on by the sides of the carrier. One 120 reason for this is that while only a slight orbital movement is necessary for the purpose of forming a type on the typebar-blank, 125

it is desirable to make provision for considerable extra throw of said die-wheel for the purpose of disconnecting the same from its driving member. This die-wheel may be rotated in any suitable manner while moving in its orbit, but for the purpose of imparting such rotary movement thereto I have shown at 31 a driven spur-gear secured to the shaft 4, this spur-gear being driven in the present 10 case by a driving-gear, preferably in the form of a fixed resistant gear or rack 32. In the construction shown the driven and driving gears are so associated that one of them will be shiftable toward and from the other in the 15 plane of the orbital movement of the driven gear, and in this case the rack is pivoted at 32' so that it may be swung down at its opposite end out of mesh with the teeth of the spur-gear 31 when the parts are in the positions shown in Fig. 1. In order that the rack 20 or segment may be dropped in this manner said rack has in the present case an extension 33 with an opening 33' therein, in which may work the eccentric portion 34', of an eccentric-stud mounted in the upright 3, and preferably having a knurled head 34" for turning the same. It will be noticed that this eccentric-pin may serve not only as a means for releasing the rack but also for taking up wear 25 between the teeth of the rack and the pinion 30 between the teeth of the rack and the pinion.

It is only necessary to release the driving and driven gears in the manner just described when it is desired to bring a different die into position for the purpose of forming another type. In order to locate any die precisely in its working position I preferably employ in connection therewith some means for indicating such precise working position, a pointer being shown herein at 35 for this purpose, said pointer being mounted in the present case on the threaded forward end of the shaft 30 and in contact with the forward cheek of the hub 30" of the lever T and being held in place by a nut 36. In order that each selected die may be properly located it will be evident that the teeth of the driving and driven gears must be properly spaced with respect to such dies, there being in this case twice as many teeth in the driven gear 31 as there are dies on the die-wheel which moves in unison with said gear.

The blank, which may be of any material suitable for the purpose but will usually be a type-metal of proper composition, is designated by *b* and may be supported by, and be movable with, a blank-holder or carrier, such as *B'*, mounted on, and movable vertically relatively to, a second blank-carrier or blank-carriage, such as *B*, which may be mounted on the base 2 so as to have a feed movement thereover, said carriage being confined in this case by suitable side guides, such as 37 and 37', and the blank itself being preferably held in place in the carrier *B*, by clamp-

screws, such as 38. Here the movable carrier B' has a bore 39 therein, in which is seated a spring, such as 39', which at its upper end is in contact with a face of the carriage B and tends to force the movable carrier B' downward, while suitable operating means may be employed for the purpose of raising the movable carrier B' at the proper time. In the construction shown an angle-lever is pivoted at 16 on the base 2, and has a short arm 15', carrying at its end an anti-friction-roll 15'', for raising the movable carrier B', while the long arm of said angle-lever is designated by 15, and has in this case an antifriction-roll 15''', co-acting with a suitable operating member—such as a cam—the movements of which are preferably controlled by the lever T. In this case said lever has formed thereon a short arm 40, to the lower end of which is pivoted, by a pin-and-slot connection, the slot of which is designated by 41', a connecting-rod 41, the other end of which is pivoted to an oscillatory arm 42, loosely mounted on a short shaft 45, journaled in the long bearing 3'', said arm 42 constituting a pawl-carrier for a pawl, such as 43, which may be pressed, by means of a spring 43', into engagement with the teeth of a ratchet-wheel 44, movable with the shaft 45, and hence serving to turn the latter step by step. A stop pawl, such as 46, held in place by a spring 46', may be employed to prevent overthrow and return movement of the ratchet-wheel. This shaft will therefore be turned step by step as the lever T is swung back and forth, it being evident, of course, that the ratchet-wheel will be turned only when the die-wheel D swings to the right, as seen in Fig. 1. The shaft 45 constitutes in the present case a means for controlling the movements of the arm 15 of the angle-lever that serves to feed the blank toward the die during the type-forming operation, and the cam which has been hereinbefore alluded to as the means for operating said arm 15 is carried by said shaft 45, said cam being shown herein at 47, and having a gradual rise 47', which will cause the blank to be raised in a corresponding manner, said cam having also a somewhat quick drop, which is clearly indicated by the line 47''. The entire operation of forming a type is carried out in this case by operating one of the dies d in contact with the blank b and feeding said blank toward the die, and the die employed is so constructed that it forms a type but does not form a space in advance of such type. A die of this construction, while operating as a single mechanical element, and while it is actually constructed in one piece, has many functions that may be carried out by a large number of tools having a single function; that is to say, it not only serves to shear out a type-block to fill the die-space.

but it also rolls the face of the type-block, swages the face of the type to form, and forges the end walls of the type.

The type-dies shown herein have only one blade each, as distinguished from the dies shown in my companion applications Serial Nos. 79,360 and 79,359 hereinbefore referred to, this blade being at the rear side of the die and being preferably of the structure shown at 5. This blade is somewhat thin and is preferably considerably thinner than the tool which serves to form the space in advance of each type. Said blade forms a means for confining endwise of the bar flowage of the stock toward the rear side of the die, the solid body of metal in the blank in advance of die that is being operated serving to confine endwise flowage at the forward side of the die, although, of course, during compression 10 surplus stock will be free to flow out crosswise of the bar. The blade 5 preferably projects throughout its whole length beyond the outer or bottom wall of the die, and hence throughout the whole period during which a type is being formed said blade serves to confine at that side of the die the mass of material that is being shaped. The bottom 6 of the die serves to roll out sidewise the major portion of the material not required for the 15 making of a type. The end walls of the die-space, which are indicated herein by 6', intersect the bottom 6 in the usual way, as at 6", and the edges 6" serve to shear or cut away from the mass of the bar a type-block 20 or type-blank containing sufficient material to fill the die-space and to form a finished type; and that part of the edge of the typebar-blank which is operated on, but is not compressed by the blade 5, and is not contained within the die-space, is compressed by 25 the bottom wall 6 of the die and is rolled off sidewise of the typebar-blank when the die-carrier D is rolled back and forth transversely to the typebar-blank, but the material so 30 rolled off is always confined endwise of the bar between the blade 5 and that portion of the stock contained in the typebar-blank immediately in advance of and below the outer forward wall 6''' of the die. Hence none of 35 this surplus material is operated on in such a manner as to force it into the field of an adjacent type or space, but instead all of the 40 excess flows sidewise of the blank and may be severed from the bar to bring the sides of 45 the latter into parallelism with each other.

The manner in which and the extent to which the type-formative material confined between the blade 5 and the stock in advance of the forward wall 6''' is operated 50 upon are dependent upon the rolling movement of the die and also upon the feed movement of the blank. In this case, as will be evident from the previous description of the feed mechanism, the blank is fed step by step 55 toward the die in a regular manner as the die

travels back and forth across the edge of the blank, and hence during the rolling movement of the die the type-forming action will be carried down into the stock through successive and substantially equal distances, although, of course, it will be understood that the effect of the rolling action upon the blank will not be the same for each operation of the die.

As in my companion applications hereinbefore mentioned, the type-forming means subjects the stock to a series of operations by means of which a type is formed without impairing the strength of the type-formative material of the typebar-blank. It has been 70 stated before that these blanks will be a suitable composition of type-metal, and moreover they may be in the form of separate typebar-blanks or a continuous strip or ribbon of metal from which the typebars may 75 be severed after being completed. In every case, however, wrought-metal blanks formed ordinarily by the usual rolling operations should be employed, as I have found in practice that cast-metal blanks are undesirable 80 for the purpose and are not so well adapted to be wrought into shape by such operations as are employed in this case. The principal reason for this is that cast-metal when rolled and forged in this manner tends to crush and 85 crumble beneath the die instead of compressing and flowing properly, and hence the cast-metal will not fill the dies so well as the wrought-metal nor form the smooth faces 90 and sharp edges that the latter will.

The manner in which a type is shaped when the blank is subjected to the action of a rolling die during the feeding of the blank toward the die is somewhat complex, but is 95 illustrated approximately in Figs. 5 to 8, inclusive, which illustrate the appearance of the forming type during certain stages of the operation. As the die is swung toward the right and toward the left alternately, the stock at the base of the type-blank or type-block 100 is forged first at the left-hand side and then at the right-hand side, the forging action being, of course, greatest near the base of the type-block and also being greater as the forging action is carried farther and farther down the stock. This forging action, 105 however, extends up the entire length of the side being operated on, and results in a thorough compacting or condensing of the particles of the blank. The forging action 110 being greatest at the base of the type-block the latter will be strengthened most in the region of its base, but the strengthened base will also be connected with the face of the type by a thick layer of condensed metal 115 thoroughly compacted by the forging operation. At the same time that this metal is compressed by the forging action of the end walls 6' of the die-space the central, upper portion of the type-blank is forced upward 120

100

into the die, owing to the resistance opposed to the forging action by the upper walls of said die-space. At each movement of the die toward the right or toward the left the metal so forced up tends to fill one side of the space 9, while the opposite side of said space forms an outlet through which the air confined between the type-blank and the die may escape. During these two movements—
 5 viz., the rolling of the die and the feeding of the blank toward the die—the cutting edges 6" of the die shear farther and farther into the metal of the typebar-blank and gradually complete the cutting out of the type-block or
 10 type-blank from the mass of the metal. This type-blank, it will be seen, is not completely sheared from the typebar-blank until the actual completion of the making of the type. In other words, the shearing of the type-
 15 blank and the formation of the type from that type-blank are substantially coincident in the present application as in my companion applications hereinbefore mentioned. Each time that a feed movement of the
 20 blank and a rolling movement of the die occur an additional portion of the surplus material confined between the die-blade 5 and the mass of metal in advance of the outer forward wall of the die is forced out sidewise
 25 of the blank principally by the bottom wall 6. After such portion of the surplus has been forced out sidewise in this manner the cutting edges 6" at the next operation shear farther into the body of the blank and the
 30 metal at the point at which such cutting edge previously operated is forced farther out toward or beyond the side of the bar.

In the mechanism illustrated the gradual formation of each type is accomplished in
 40 twenty-four strokes of the lever T, twelve in each direction, and Figs. 5, 6, and 7 respectively illustrate the first, an intermediate, and the final positions of the die and the blank, Fig. 7 illustrating how the blank is
 45 permitted to drop at the end of the operation in order to separate the die and the blank without impairing the finished type, although these parts need not be separated, unless desired, until after the completion of the space
 50 in advance thereof.

As before stated, the space-forming means or space-forming tool for forming the space in advance of each individual type may operate in any suitable manner, provided that such operation does not begin until the completion of the operation of the type-forming means. As the mechanism shown in the present application is intended to form the type and the space successively, the latter after the completion of the former, the stock contained in the space-field, which is the space occupied by the material upon which the space-forming tool operates, will not be disturbed at all during the type-forming action, and hence the support which it is

necessary to preserve at the forward side of and below the forming type for the purpose of preventing imperfect location of such type will not be at all impaired when the space-forming means operates in this manner. 70

Either the typebar-blank or the space-forming tool may be operated in contact with the other to form a space in advance of the type, but I prefer to actuate the cutter itself, and in the construction shown this is 75 preferably a milling-cutter, such as c, normally supported in a position where it will clear the edge of the typebar-blank throughout the whole of the type-forming operation, it being preferably carried by a cutter-bar or 80 cutter-carrier 20, supported at some suitable point, such as 22, on the framework, said cutter-carrier having thereon in this case a bracket 20', containing a bearing in which is journaled one end of a short shaft, such as 85 21, the opposite end of which may be journaled in a bearing in the main portion of said cutter-bar, said short shaft carrying in this case a gear, such as a bevel-pinion 21', which may mesh with a corresponding bevel-pinion 23', carried at one end of a side shaft 23, journaled in this case in bearings in a pair of lugs 24 and 24', projecting from the side of the cutter-bar, said shaft 23 having at its opposite end another bevel-pinion 23", 90 meshing with a corresponding bevel-pinion 22', carried by the shaft 22, which forms the pivot of the cutter-bar 20, said shaft being journaled in suitable bearings at one end of the framework and carrying a band-wheel 100 22", by which said shaft, and hence the cutter c, may be continuously rotated. The cutter-bar, and hence the cutter c, should normally be held up out of engagement with the blank b, and when in its normal position 105 said cutter should clear the typebar-blank even when the latter is raised to the limit of its upward movement. In this case a spring 25 is employed for holding the cutter up away from the work. 110

The cutter-bar preferably has a handle at its free end for operating the same, and it is intended to press this cutter-bar down by hand after a type has been formed and while the cutter c is being rotated. As soon as the 115 cutter-bar is depressed to the proper point the tool will begin to cut away the stock contained in the space-field in advance of the last formed type, and such space-forming or milling operation will continue until the 120 cutter-bar reaches the limit of its downward movement. This limit should be determined by a suitable stop face, and I have shown at 26 an adjustable stop-screw supported on the framework in a position for 125 limiting the descent of said cutter. This stop should be adjusted so as to check such descent of the cutter-bar and its cutter when the lowermost cutting point of the milling cutter is substantially at the same depth to 130

which the blade 5 of each die operates; that is to say, the space may be carried down to a point slightly below the base of the type formed in advance thereof. The cutter 5 which I prefer to employ is one having teeth both on its periphery and on its forward side, the peripheral cutting teeth being designated herein by c' and the side cutting teeth by c'' , and hence the space s formed by the 10 cutter will have a forward wall which will be inclined forward from the bottom to the top of such space. In order that this space may be formed immediately in advance of a simultaneously formed type it is, of course, 15 necessary that the rear face of the cutter c be so positioned as to operate upon the blank substantially in the plane of connection of the type-field and the space-field in advance thereof, and preferably the rear face of this 20 cutter will lie against, and be substantially coincident with, the extreme, forward, outer wall of the die, and hence the die and the cutter, though they will operate upon the blank at different times, may work in con- 25 tact with each other, the die serving first to form a type, and roll away surplus material, from that portion of the stock within the space-field without encroaching upon the stock of the space-field in advance thereof, 30 and the cutter serving to remove, after the completion of the type-forming operation, all that portion of the stock which lies within the space-field; and when these parts operate in this manner it will be evident (see par- 35 ticularly Fig. 10) that no part of the space in advance of a type is formed by the die which makes such type.

After the completion of any type and the subsequent formation of the space in ad- 40 vance thereof a new type, and also a corre- 45 sponding space, may be formed by the same die and the cutter or by bringing another die into position to coöperate with the mill- 50 ing-cutter. In order to present a new por- 55 tion of the blank to the action of such die and the cutter suitable feed mechanism may be used, and in the construction shown the carriage B has depending therefrom a lug 60, which is bored to form a nut, through 60 which may be passed a screw-thread, such as 61, having a round shank 61', journaled in a bearing 62, at one end of the base 2, and preferably having secured thereto a handle 61'', for turning said screw. Each turn of 65 this screw may represent a unit distance corresponding to a unit of width of a type to be formed, and by turning the handle 61'' the proper number of times the blank may be fed forward any given number of units corresponding to the width of the type to be 70 formed by any particular die which may be brought into action.

The fins f and f' , which are rolled off by the die during the formation of each individual type, may be removed in any suit-

able manner, usually by means of planing cutters, (not shown,) to bring the sides of the bar into parallelism with each other.

Having described my invention, I claim—

1. In a typebar machine, the combination 70 with a blank holder for a typebar blank, of a type die; means for imparting a relative curvilinear working movement to the die and typebar blank to form a type on the edge of the blank, and means for independently 75 forming a space in advance of the type after the completion of the said type.

2. In a typebar machine, the combination 80 with a blank holder for a typebar blank, of a type die; means for rolling the typebar blank and type die in contact one with the other to form a type on the edge of the blank, and means for independently forming a space in 85 advance of the type after the completion of the said type.

3. In a typebar machine, the combination 90 with a blank holder for a typebar blank, of a type die; means for imparting a relative working movement to the die and typebar blank to form a type on the edge of the blank; means for independently forming a space in advance of the type after the completion of the said type; and means for feed- 95 ing the type-making members together during the type-making operation.

4. In a typebar machine, the combination 100 with a blank holder for a typebar blank, of a type die; a separate rotary space-forming tool; means for imparting a relative working movement to the die and the typebar blank 100 to form a type on the edge of the blank, and means for rotating the space-forming tool in contact with the blank to form a space in advance of the said type.

5. In a typebar machine, the combination 105 with a blank holder for a typebar blank, of a type die; a separate rotary space-forming tool; means for imparting a relative working movement to the die and the typebar blank 110 to form a type on the edge of the blank while the forming type is supported at its forward side by adjoining stock; and means for rotating the space-forming tool in contact with the blank to form a space in advance of the said type.

6. In a typebar machine, the combination 115 with a blank holder for a typebar blank, of a type die; a separate rotary space-forming tool; means for imparting a relative working movement to the die and the typebar blank 120 to form a type on the edge of the blank; and means for rotating the space forming tool in contact with the blank after the completion of the type, to form a space in advance of the said type.

7. In a typebar machine, the combination 125 with a blank holder for a typebar blank, of a type die; a rotary space forming milling cutter; means for imparting a relative working movement to the die and the typebar blank 130

to form a type on the edge of the blank; means for rotating said milling cutter in contact with the blank; and means for feeding the blank and the said cutter together to 5 form a space in advance of the said type.

8. In a typebar machine, the combination with a blank holder for a typebar blank, of a type die; a rotary space-forming milling cutter having a bevel toothed forward side; 10 means for imparting a relative working movement to the die and the typebar blank, to form a type on the edge of the blank, and means for rotating the milling cutter in contact with the blank to form a space in advance of the said type.

9. In a typebar machine, the combination with a blank holder for a typebar blank, of a type die; a rotary space-forming milling cutter, operative in a path the rear edge of 20 which is substantially coincident with the path of operation of the forward wall of the die; means for imparting a relative working movement to the die and the typebar blank to form a type on the edge of the blank, and 25 means for rotating the milling cutter in contact with the blank to form a space in advance of the said type.

10. In a typebar-machine, the combination, with a blank-holder for a typebar-blank, of a type-die; a rotary space-forming milling-cutter; means for reciprocating said die in a curvilinear path in contact with such blank to form a type on the edge of the blank; and means for rotating said milling-cutter in contact with the blank, after the completion of said type, to form a space in advance of said type.

11. In a typebar machine, the combination with a blank holder for a typebar blank, 40 of a type die; a separate rotary space-forming tool operative in a path which is the supplement of the path of operation of the die; means for imparting a relative working movement to the die and the typebar blank to 45 form a type on the edge of the blank while the forming type is supported at its forward side by adjoining stock; and means for rotating the space-forming tool in contact with the blank to form a space in advance of the said 50 type.

12. In a typebar-machine, the combination, with a blank-holder for a type-bar-blank, of a type-die; means for subjecting such typebar-blank to compression in contact with said 55 type-die to form a type on the edge of such typebar-blank; and separate space-forming means for removing from the blank, after the completion of the type, excess material in advance of said type.

60 13. The combination with selective dies and mechanism for rolling a blank in contact with the dies selectively to thereby form a line of type, of a space-forming instrumentality independent from the dies, mechanism for operating such instrumentality

subsequently to the operation of each selected die.

14. The combination with selective dies and mechanism for operating the dies to form a line of type by rolling a blank against 70 such die, of a space-forming instrumentality independent from the dies, mechanism for operating such instrumentality subsequently to the operation of each selected die, and mechanism for feeding each operating die, 75 and the space-forming instrumentality into the blank.

15. The combination with selective dies and mechanism for operating the dies to form a line of type, such mechanism comprising 80 means for rolling a blank by the type-forming mechanism, of a space-forming instrumentality independent from the dies, mechanism for operating such instrumentality subsequently to the operation of each selected die, mechanism for feeding each operating die and the space-forming instrumentality into the blank, and means for shifting the blank longitudinally to bring each selected die in turn into coöperative relation 85 with its corresponding type-blank portion of 90 the type-bar blank.

16. The combination with an adjustable die carrier, selective dies mounted thereon and mechanism for operating the carrier 95 after each adjustment to thereby form a line of type on a blank, of a space-forming instrumentality independent from the dies, and mechanism for operating such instrumentality subsequently to the operation of 100 the die carrier for rolling the blanks by the type-forming mechanism.

17. The combination with an adjustable die carrier, selective dies mounted thereon, mechanism for operating the carrier after 105 each adjustment to thereby form a line of type on a blank, the blanks being rolled by the type-forming mechanism, of space-forming instrumentalities independent from the dies, mechanism for operating such instrumentalities subsequently to the operation of the die carrier, mechanism for feeding each 110 operating die and the space forming instrumentality into the blank, and means for shifting the blank longitudinally.

18. The combination with blank rolling and die mechanism for forming types, of independent space-forming mechanism operative subsequently to the operation of the blank-rolling mechanism.

19. The combination with selective dies and mechanism for rolling the blank with each selected die in turn to thereby form a line of type, of a space-forming instrumentality separate from the dies, and mechanism for operating such instrumentality subsequently to the operation of each selected die.

20. The combination with selective dies and mechanism for rolling the blank with 130

each selected die in turn to thereby form a line of type, of a space forming instrumentality separate from the dies, mechanism for operating such instrumentality subsequently to the operation of each selected die, and feed mechanism for feeding each operating die and the space-forming instrumentality into the blank.

21. The combination with an adjustable die carrier, selective dies mounted thereon and mechanism for die-rolling the blank in a direction transverse to the line of length thereof, of a rotative space-forming instrumentality operative in a plane transverse to the line of length of the blank and subsequently to the operation of each selected die.

22. The combination with an adjustable die carrier, selective dies mounted thereon and mechanism for die-rolling the blank in a direction transverse to the line of length thereof, of a rotative space-forming instrumentality operative in a plane transverse to the line of length of the blank and subsequently to the operation of each selected die, feed mechanism for feeding each selected die and the space-forming instrumentality into the blank, and means for shifting the blank longitudinally.

23. The combination with mechanism for die-rolling a blank cross-wise by repeated movements to form a type gradually and by repeated reductions, of a separate space-forming mechanism operative subsequently to the operation of the die operating mechanism.

24. The combination with selective dies adapted to form a succession of types each by a succession of gradual reductions, and mechanism for rolling the blank with each selected die in turn to thereby form a line of type, of a space-forming instrumentality separate from the dies, and mechanism for operating such instrumentality subsequently to the operation of each selected die.

25. The combination with selective dies adapted to form a succession of types each by a succession of gradual reductions, and mechanism for rolling the blank with each selected die in turn to thereby form a line of type, of a space forming instrumentality separate from the dies, mechanism for operating such instrumentality subsequently to the operation of each selected die, and feed mechanism for feeding each selected die and the space forming instrumentality into the blank.

26. The combination with an adjustable die carrier, selective dies carried thereon and adapted to form a succession of types each by a succession of gradual reductions, and mechanism for die-rolling the blank in a direction transverse to the line of length thereof, of a rotative space-forming instrumentality separate from the dies, and mechanism for rotating such instrumentality in a plane transverse to the line of length of the blank and

subsequently to the operation of each selected die.

27. The combination with an adjustable die carrier, selective dies mounted thereon and adapted to form a succession of types each by a succession of gradual reductions, and mechanism for die-rolling the blank in a direction transverse to the line of length thereof, of a rotative space-forming instrumentality, mechanism for rotating such instrumentality in a plane transverse to the line of length of the blank and subsequently to the operation of each selected die, feed mechanism for feeding each operating die and the space-forming instrumentality into the blank, and means for shifting the blank longitudinally.

28. The combination with die operating mechanism, of a space forming instrumentality adapted to form, between consecutive types, a space prior to the making of the next type in advance along the blank.

29. In a typebar-machine, the combination, with a blank-holder for a typebar-blank, of a type die, a separate space-forming tool, and means for giving the die and the typebar-blank a rocking movement with respect to each other to form a type on the edge of the type-blank, and independent means for forming a space in advance of the type after the completion of the said type.

30. The combination with die operating mechanism, of a space forming instrumentality, and means for actuating said space forming instrumentality succeeding the formation of the last formed type to form a space between such last formed type and the unworked upon blank.

31. The combination with die operating mechanism, of a space forming instrumentality, and means for actuating this for forming spaces in excess of those required for letter spaces between the types after completion and the unworked blank.

32. The combination with a plurality of rotary dies, a blank holder, means for causing one of these to approach the other for a working movement, and a rotary space cutter having an axis of rotation different from the axes of rotation of the dies.

33. The combination with a die carrier, means for rotating and orbitally moving the same, a space cutter and means for rotating and orbitally moving the same about axes different from those of the die carrier.

34. In a typebar-machine, the combination with a blank holder, of dies operable upon a blank held thereby, a rotary space forming milling tool having teeth upon one side and a plane face upon the other side, means for bringing the dies selectively to the blank, and means for thereafter bringing the milling tool to the blank with its plane face toward the completed type.

35. In a typebar-machine, the combina-

tion with a blank holder for a typebar, of a series of type dies, means for bringing these selectively to the blank, a milling tool and means for bringing the same to the blank to space the same by cutting away the un-worked upon portion of the blank adjacent to the last formed type.

36. The combination with a blank holder, of type dies for selectively working thereon, and means for cutting away the blank adjacent to each type after its completion.

37. In a typographic machine, the combination with a blank holder, of a series of dies, means for selectively bringing these into working relation with a blank in said holder for successively working upon portions of the blank, and means for cutting away portions of the blank adjacent to such

portions and working into the same toward the blank and away from the worked upon portion.

38. The combination with blank holding mechanism, of type forming mechanism, means for actuating one of these elements to form the type by a rolling action, and a space forming instrumentality comprising a milling tool operative independent of said type forming mechanism subsequently to the formation of each successive type to form a space between the last formed type and an unworked upon portion of the blank.
